REPEATING SAFETY RAZOR

Ralph G. Arey, Brockton, Mass.

Application March 26, 1948; Serial No. 17,164

5 Claims. (Cl. 30—40)

1

My present invention relates generally to safety razors, and more particularly to a novel and improved construction of a repeating type razor including a unique blade assembly for association therewith.

The prime object of my present invention pertains to a repeating type safety razor having a novel head portion so arranged and constructed that a multi-blade-carrying blank or blade assembly may be inserted, housed, and protected therein, that each blade carried by said blank may be successively advanced into shaving position, that each used blade may be individually detachable, and that a subsequent blank may be installed without disassembling or disturbing any part of the razor head.

Another main feature of my invention is the provision of a novel operating spring slide which is movably connected with the head portion and adapted, thru cooperative means thereon on the razor head and on the blade-carrying blank, to feed each blade into positive shaving position, and to lock the blade automatically when so moved, all with a single motion and by a simple and efficient construction.

A further important object of my invention resides in the novel blade assembly, which, in effect, constitutes a multi-blade-carrying blank wherein a predetermined number of relatively narrow thin blades in adjacent but spaced relation to each other are assembled, by spot welding or other suitable means, on a carrying element, said carrying element being positioned on the top or the upper side of the blades, thus reinforcing the thin blades as well as affording blade-cutting edge protection.

An additional advantageous feature consists in the blade assembly of the plurality of thin blades attached to and supported by the carrying element with the blades attached thereto on one side in spaced relation and with pre-formed lines, perforations, indentations, or the like to facilitate the detachment of the used blade without injury to the cutting edge of the succeeding blade. For this purpose I form the parting lines of that part of the carrier which is attached to one blade at a slight but appreciable distance back of the cutting edge of the succeeding blade, and the razor head and blade carrier are so constructed and arranged to necessitate the detachment of the used blade in a direction away from the succeeding blade, thus effectually preserving the cutting edge for shaving use.

A most important and further feature and advantage of my present construction is that I

have devised a novel and efficient method of loading or uniting the carrier blank with a plurality of blades thereon with the razor head, feeding the entire blade assembly with a plurality of blades in protected attachment with the carrier into the head-receiving, holding, feeding, and locking devices. Thus my present invention and method consists in wrapping or enclosing a set or series of blades on a carrier, such for example as seven blades, one for each day of the week, on one carrier, packaging the same in a protective envelope or covering, which envelope can be partially opened and thereupon the blade assembly fitted to and loaded into the head, which process and assembling of the carrier and its attached blades is effected while still held in protective wrapping so that the user's hands or fingers never contact the blades during such loading action into the razor head, thus preventing danger of cutting the fingers or desterilizing the blades themselves. Thus, the cutting edge of each blade is protected and unexposed until moved into shaving position, the cutting edges being protected from injury, nicking, contamination, being maintained in a hygienic state, untouched by human hands, from the manufacture to the actual shaving action.

Also, another important and advantageous feature is that my present construction permits the manufacture of such extremely thin blades and the uniting of same to a carrier to support and reinforce the blades, and the packaging of the same may be accomplished as a continuous automatic operation at a high speed and low cost by relatively simple and efficient equipment.

Long lengths of the carrier can thus be utilized to receive successive blades in spaced relation, which are spot-welded to the carrier and run off in conveyor lengths to be subsequently severed into a selective number, such as seven blades on a carrier section, giving a fresh blade for each day of the week in the unit or blade assembly, which is then packaged and subsequently assembled when desired into the razor head as above explained. The blades can be treated with a protecting film and thus preserved by the packaging so that each blade is fitted in the razor head and moved in the shaving position in its best possible and original condition for sharpness and efficiency.

A still further object of my invention is to construct a safety razor of the repeating type, which, in addition, includes such desirable features of the well known separate blade type of safety razor as handy and convenient size, thin-

ness of head construction, lightness of weight, and easy cleanability.

Still further features of my invention apply to the extreme simplicity of my repeating safety razor, the ease and efficiency of its operation, its relatively low cost of manufacture, and with a single moving element which serves to protect, to hold, to feed, and to lock the carrier and blades.

Also my invention provides for the wrapping or packaging of a considerable number of blades in a single wrapping, such for example seven blades and the attached carrier, all enclosed in a single envelope or wrapping and this multiplicity or plurality of blades is positioned simultaneously in the razor head by a single loading operation.

Further advantageous features, novelties, combinations, and pertinent details will be herein-after more fully pointed out and claimed.

Referring to the drawings showing a preferred embodiment of my present invention and the novel method of uniting or loading the blade assembly into the razor:

Fig. 1 is a side view of my present device;

Fig. 2 is an enlarged cross-sectional view of the head and the blade assembly fitted therein, on the line 2—2 of Fig. 5;

Fig. 3 is a similar cross-sectional view illustrating the movable element in a retracted position prepared to feed forward the carrier and a new blade, on the line 3—3 of Fig. 5;

Fig. 4 is a similar cross-sectional view with the feeding element in forward position and a used blade positioned or adapted to be detached;

Fig. 5 is an enlarged cross-sectional view on the line 5—5 of Fig. 4;

Fig. 6 is an enlarged cross-sectional detailed view illustrating the assembly of carrier and blade with the lines of detachment for sections of the carrier;

Fig. 7 is a plan view of the head of the carrier with the feeding element in retracted position;

Fig. 8 is a side view of the same;

Fig. 9 is a view of one method of packaging the blade assembly;

Fig. 10 is a side view illustrating the loading operation with the blade assembled in the package of Fig. 9.

Figs. 11 and 12 show modified forms of packaging the blade assembly, and

Fig. 13 is a plan view on an enlarged scale of the carrier and seven blades welded thereto with the blades in uppermost position.

Referring to the drawings, my novel and improved razor comprises two parts, a fixed element and a movable element, which are at all times in united and assembled relation and in position to receive and intermittently feed forwardly the carrier and its attached blades a proper distance to bring successive blades into operative relation and permit detachment of a used blade. The fixed part comprises a base 1, handle 2, and a uniting gooseneck 3, which latter is preferably provided with a ferrule 4 covering the adjacent end of the handle 2 and a disc 5 welded or otherwise secured to the bottom of the base 1.

The handle may be of any suitable material such as plastic, and the gooseneck and base are preferably of metal, the gooseneck giving a desirable and convenient angle between the handle and the razor, said gooseneck extending beyond the ferrule and into the handle 2 or united in any other desirable manner. The base 1 is of appropriate width and area to receive a carrier

with a plurality of blades attached thereto, viz., seven as shown in Fig. 1, and is formed with a curved guard 10 at the shaving end, viz., the right viewing Figs. 1 to 4, said base 1 having side flanges 12 and 14 extending upwardly at substantially right angles to the base 1, each flange having a slightly inturned upper ridge 15—15 for added strength and smoothness in sliding the razor along the skin of the user. Each flange 12 and 14 is formed with an inner cam surface 16 ending in a rearwardly formed hook 18, which cam surfaces and hooks in the side flange constitute bearings and a spring-loading action as well as a stop to limit the extent of movement of the movable member, which latter I designate generally at 20 and is formed with a top plate 21, and a bottom plate 22, the same being of spring metal and of U-shaped form.

The width of the top plate 21 is sufficient to constitute a sliding fit between the inner surfaces of the side flanges 12, and the forward edge of the top plate 21 has a pair of laterally extending prongs 25—25, which prongs fit into the cam paths 16, the U-shaped form of the movable member 20 forcing the top plate and these projections into spring-pressed engagement with the cam surface and the curve 19 at one end of the cam surface and the curve 19 at the forward end of said cam surface constitute stops limiting the forward and back movement of the member 20.

Each side flange is cut away below the cam surface and hook, as clearly shown in Figs. 2 and 3, and leaving a slightly upturned edge 13 which constitutes side guides for the bottom plate 22 of the movable member 20. These side flanges 12 also are inclined at a predetermined contour from the ridge 15 downwardly to the curved guard 10, as indicated at 28, see Figs. 2 and 3, thus facilitating the presentation of the cutting edge of the blade in cooperation with the curved guard 10 to facilitate the shaving operation.

The spring action on the top surface 21 caused by the riding of the projections 25 in the cam grooves is further effected by a pair of projections 29—29 on the bottom portion 22 of the movable member, which projections ride upon a slight cut-away portion of the bottom member 13 of each side flange 12, which cut-away portion also constitutes a stop for the forward movement of the member 20 in addition to or independently of the terminus of the cam path 16, as shown at 19, and already described.

In order to facilitate the feeding of the carrier and its attached blank to the razor head, comprising the base 1 and movable member 20, the rearmost end of the base 1 is curved as shown at 11 substantially corresponding to the curved guard portion 10 at the opposite end, and I arrange the movable member 20 when in retracted position to be slightly overhanging this curved member 10 and thus provide a convenient throat into which the carrier and its attached blades may be applied when the razor is being loaded for use.

In order to afford a step-by-step feeding and locking action, I arrange the carrier 30 with a series of blades 33 attached thereto transversely, each with its shaving edge 34 facing in the same direction and preferably welded to the carrier by points as indicated at 35, said carrier having a series of holes or openings 36—36 along each side edge portion, which will leave spaces between the adjacent blades, as clearly shown in Fig. 13. Cooperating and in alignment with

these openings 36 on each edge of the carrier; I arrange on each edge portion of the lower part 22 of the movable member a set of lugs 38 and 39. These lugs are stamped out in the form of a slightly bevelled edge, see Figs. 2 and 4, whereby they constitute a sufficiently firm engaging device while permitting springing backwardly and in non-locking engagement during the reciprocating action of the movable member.

When the carrier 30 and its attached blades are fitted in the razor, and with the carrier on the topmost surface in contact with the lower portion 22 of the movable member 20 and forced forwardly, lifting the front edge portion of the lower plate 22, it thereupon snaps the rearmost lug 39 into engagement with the openings 36 at the back of the rearmost edge of the adjacent blades. A forward movement of the member 20 thereupon feeds the carrier and blades forwardly sufficiently to be engaged by the second pair of lugs 38 and to thereupon position the first razor blade in shaving relation to the guard 10.

I preferably form a series of openings, here shown as three in number, designated at 40 at each side of the base 1 in alignment with these lugs 38 and 39, which will thus still further serve to snap into holding position in the openings 36 in the carrier. In order to hold the carrier and blades from being retracted during retractive movement of the member 20, I stamp upwardly from the base 1 a set of projecting lugs 41 and 42, which are sufficient to engage behind the spaced blades and prevent the carrier attached thereto from being retracted during the retraction or rearward movement of the member 20. As the movable member 20 is pushed forwardly or to the right, viewing Figs. 1, 2, 3, and 4, the tension on the bottom layer 20 is increased owing to the traversing of the cam paths 16 by the projections 25 on the upper plate 21, and thus the forward edge of the lower plate 22 exerts an increased tension on the carrier and blades as the same is moved adjacent the guard 10; thereby more firmly locking the carrier and its foremost and exposed blade 33 into shaving position.

After this blade has been used, the member 20 is retracted and again moved forwardly, the projections 38 and 39 riding upwardly over and backwardly on the top of the carrier between the openings 34 along each edge while the carrier and blades are held by the lower projections 41 and 42, and thereupon a succeeding forward motion of the member 20 permits the projections 38 and 39 to snap into the openings in the carrier and feed forwardly the entire carrier and its blades, presenting a succeeding blade 33 into shaving position.

It is now desirable to detach the used blade and the portion of its carrier to which the blade is welded or united, and expose the new edge of the succeeding blade in position for use. For this purpose I form weakened sections or perforations 45, see Fig. 6, along the carrier spaced somewhat back from the edge 34 of each blade so that the used blade and its attached portion of the carrier may be quickly and easily detached by bending up the same, as shown in Fig. 4, and thereby detaching it and presenting a new blade ready for use. By thus bending the used blade and attached carrier upwardly, the sharp edge of the succeeding blade is not marred, damaged, dulled, or affected while the previously used blade is removed.

As shown in Fig. 7, I may provide a series of openings 44—44 in the curved end of the guard

10 which will permit the razor to be held under a faucet or dipped in water to clean the same, but this is optional and the guard 10 may be formed with slotted openings, if desired.

Figs. 7 and 8 are illustrative of the manner of assembling the movable member 20 and base 1, but when once thus assembled the two parts need not again be separated and, hence, there is no danger of dropping, losing or misplacing the movable member from the entire head.

My novel method of loading the carrier and its attached blades is illustrated in Fig. 10 although the carrier and blades can, of course, be fitted in between the U-shaped portion of the member 20 and the rearwardly curved edge 11 of the base 1, as above explained. However, in order to maintain the blades in perfect condition, I prefer to enclose the same in a package or wrapper and upon partially opening or undoing the package, the same may be utilized to feed the carrier and blades into the head without touching either the blades or carrier and without danger of injury either to the user or to the cutting edge of each blade, which is hereby protected until actually fitted within the head and ready to be fed forward step-by-step, as above described.

For this purpose, as shown in Fig. 9, I may package the carrier 30 and its attached blades in a folded sheet 50 with the open ends of the sheet slit into an envelope 51. Thus the entire set of blades is enclosed and protected by the package and ready for use. By grasping the folded sheet 50 and its enclosed carrier and blades, the user withdraws the same from the envelope 51 and presents the open end to the throat between the U-shaped portion of the member 20 and the curved end 11, as shown in Fig. 10. The sides of the paper envelope 50 will be easily deflected, as illustrated, and the carrier forced inwardly, lifting the lower plate 22 until the carrier is engaged by the first lug 39; whereupon continued movement of both lug and member 20 will be effected to bring the lugs 42 into engaging position; and thereupon successive reciprocations of the member 20 will serve to feed the carrier and blades step-by-step forward, as above explained.

As shown in Figs. 11 and 12, a modified form of wrapping comprising a sheet 55 in which the entire series of blades and attached carrier are folded is illustrated at Fig. 12, the wrapping 55 being partially opened by lifting the flap 56 or 57 and thereafter loading the head by a similar movement to that described in connection with the showing of Figs. 9 and 10.

I believe that a razor having means for receiving a plurality of thus wrapped blades and simultaneously feeding the same into shaving position without detaching the wrapping until the blades are fed into operative association with the razor head or structure is a distinct novelty and is one of the features I wish to claim broadly herein.

I claim:

1. In a razor of the kind described, a fixed element and a forwardly and backwardly movable element constructed and arranged to receive, hold, and feed a carrier having a plurality of blades secured thereto, means limiting the relative movement between said fixed and movable elements, and means automatically actuated to apply pressure on the carrier and blades at the forward end of a movement, and releasing said pressure on reverse movement.

2. In a razor of the kind described, a fixed element and a reciprocating movable element constructed and arranged to receive, hold, and feed a carrier having a plurality of blades secured thereto, means including a cam on the fixed element cooperating with a part of said movable element to automatically apply pressure on the carrier and blades at the forward end of the reciprocating movement, and releasing said pressure on reverse movement.

3. In a razor of the kind described, a fixed element and a relatively movable element constructed and arranged to receive a carrier and blades, and feeding the same intermittently during the relative movement between said elements, said relative movement being forwardly and backwardly, impositive locking means at the limit of the forward and backward movements, in combination with means effective to exert a holding pressure on the carrier and blades when in the forward locked position.

4. A razor of the kind described, comprising a head having a portion fixed thereto and a reciprocating movable element longitudinally slidable therein, said fixed portion and movable element being constructed and arranged to provide a space to receive a package of detachable blades therebetween, cooperating means on said fixed and movable elements to provide for an individual blade to be detached from said package during the forward movement of said sliding element, and means on said fixed element cooperating with

said sliding element at its forward limit of movement to exert holding pressure on the next succeeding undetached blade.

5. In a razor of the kind described, a fixed element adapted to carry a movable element relatively reciprocable therein, said fixed and movable elements being spaced to receive therebetween a plurality of blades attached together, cooperating means on said fixed and movable elements to simultaneously feed said plurality of blades and detach an individual blade therefrom during the forward movement of said reciprocating element, cam slots on said fixed element engaged by a portion of said movable element to exert a holding and locking pressure on an undetached blade at the forward limit of movement of said reciprocating element.
